UNITED STATES PATENT OFFICE

CLINTON W. BROWN, OF MORRISVILLE, AND JOHN A. SOISSA, OF PHILADELPHIA, PENNSYLVANIA, ASSIGNORS, BY MESNE ASSIGNMENTS, TO SLOANE-BLAUBON CORPORATION, OF NEW YORK, N. Y., A CORPORATION OF DELAWARE

CONTROL DEVICE

Application filed February 4, 1930. Serial No. 425,755.

This invention relates to printing machines and particularly to flexibly controlled printing machines of the type in which a series of printing members are arranged and operated to print each a different part of a design or apart of different designs in such order as to form a succession of complete individual designs upon a relatively long web of material intermittently fed into and through the machine. The invention also relates to a flexible control for such machines. In the printing of rug designs upon a long web of material, such as asphalt impregnated felt base material employed in making floor coverings, it is very desirable not only to be able to print a comparatively large variety of lengths of rugs in a single machine, but also to be able to readily change the design being printed and also to be able to change the order in which parts of the design are printed. Various mechanical means have been devised and utilized for controlling the operation of the printing members of printing machines of this general type to cause them to print at the desired points and in the desired order upon the web of material so as to form a succession of complete designs, and provision has been made for varying the order of operation and the number of printing members in order to permit the adaptation of the machine to different designs; but the changing from one design to another or from one order of operation to another with these previously known controls has heretofore involved considerable adjustment of the control mechanism, requiring the expenditure of considerable time and skill in determining and effecting the proper adjustments to be made.

The present invention aims not only to simplify the control of the order of operation of the printing members of a machine of the aforementioned type and the adjustment from one order of operation to another, particularly in those machines that employ a plurality of sets of printing members such as field members and border members, etc., but also to provide for a greater flexibility of adjustment, that is, adjustment of the control to handle more complicated designs than have heretofore readily been practicable in

machines of this type, e. g. designs comprising complicated color effects, and to change from one design or sequence of designs to another without interrupting or interfering with the operation of the machine.

It is also an object of the invention to provide for more complete and more centralized control as well as a simpler control than has heretofore been available.

In the printing of a series of rug or others designs upon a relatively long web of material, e. g., the asphalt impregnated felt base material hereinabove referred to, it is essential to the most economical use of the material that the designs shall be completed as close as possible on either side of, but not overlap, defective portions of the material or breaks in the web. If the length of the web be an even multiple of the design length, and the web is free from defects which would make any part unsalable, the series of designs may be printed uninterruptedly without any great difficulty in making economical use of the material. If, however, the length of the web is not an even multiple of the design length and/or if the material has defects in it the overlapping of the end or the defects by a design would spoil the entire portion of the web covered by these designs, thus multiplying many times the loss occasioned by each defect or break. The ordinary printing machines have not provided any means which could be used with sufficient economy to save the loss thus occasioned.

One of the objects of the present invention is so to construct and arrange the control of the operation of the printing blocks that the printing of designs in predetermined order may be automatic as long as it is desired to print the design sections in uniform sequence, but so that it will, nevertheless, be subject to such easy and quick modification while the machine is running, that the operator may vary one or more designs at will and thus interpose a shorter or a longer design between the last automatically printed design and a flaw or break which would fall within the regular design if repeated. It is thus an object of our invention to put the control of the design at the finger tip of the

operator so that he may, while watching the material for flaws, change the design so as to utilize to advantage the entire portion of the web material which is free from flaws, 5 or may leave as much of it as may be desired unprinted.

A particular object of the invention is to facilitate the printing on any portion of the material of any design or any portion of a 10 design represented by any block or group of blocks set up in the machine, or the leaving of any portion of the material unprinted at the will of the operator. Other objects are the improvement of the individual means for 15 controlling the operation of the printing members and the putting of the automatic control of these means in compact form and at a point on the machine where it is readily accessible for adjustment and manipulation 20 by the operator.

Another object of the invention is to construct and arrange the control of the operation of the printing blocks in such manner as to be able to quickly and readily set the 25 machine so that the blocks will print in a prearranged order, or as quickly and readily to change the setting so that the automatic printing will be in a different order. It is also our object to make the control always 30 capable of manual manipulation to temporarily change the automatically operated sequence, but so that when the manual control is relinquished the automatic sequence will at once begin again.

Other objects and important features of 35 the invention will appear from the following description and claims when read in connection with the accompanying drawings, in which:

Figure 1 is a diagrammatic representation 40 of the machine showing the arrangement of the printing heads along the path of travel of the web of material and the arrangement of the control mechanism adjacent to the end 45 of the machine at which the material enters;

Figure 2 illustrates more in detail the 50 printing head and the electrical locking mechanism for rendering the printing head temporarily inoperative;

Figures 19 to 23 illustrate diagrammatically various set-ups for accomplishing different results with the apparatus of our invention; and 100

Figure 24 represents the sequence of operations in certain of the parts in a preferred embodiment of the invention.

In the drawings a conventional type of flat bed block printing machine is illustrated in which there is a bed 2 over which the material 4 to be printed is moved forward intermittently in steps of equal length by suitable mechanism not shown. A number of printing blocks 6 are carried upon presses 5, each printing block having a portion of the design to be printed on the material and being located above the material moved over the bed 2. The blocks 6 are each raised into the inoperative position shown in Figure 1 and lowered into the printing position and into engagement with the material to be printed by cams 8, one on each side of the bed 2, secured to rotating shafts 10. The cams 8 engage rollers 12 carried by slide carriers 14 to the upper ends of which the printing blocks 6 are secured. 110

Each machine may include as many printing blocks as desired, twenty-four blocks being a number often employed. The printing blocks are ordinarily 18 inches wide and spaced apart a distance of 18 inches. The material is moved forward in intermittent steps of 18 inches each so that adjacent sec- 120

130

tions of the material alternately come under the printing blocks, i. e. each is printed on in one operation and is between the printing blocks during the following operation of the 5 presses.

The machine illustrated in the drawings and shown diagrammatically in Figure 1 is one adapted for multicolor printing operations. In machines of this type each block as 10 it prints applies one color to the section of material beneath it, after which the material is moved forward until that section is in position beneath another block which prints another color on the same section of material. 15 In this way any number of colors may be applied to any given section of material depending upon the number of blocks employed for printing that section of the material.

When adjacent sections of the material are 20 to be printed with different designs or different portions of the same design, as in printing rugs having borders extending across the material, or in printing complex designs on the material, it is necessary to 25 "latch up" or render inoperative certain blocks while printed sections of the material pass beneath those blocks and to release other blocks to print on those sections of the material which have been left unprinted by the 30 other printing blocks.

In normal operation the slide 14 carrying the printing block 6, is lifted by the cam 8, acting through the roller 12, to a position where it is clear of the web and in which the 35 block 6 may be covered with paint or ink. When the web is in printing position the cam reaches its low portion and the slide 14 is permitted to fall by its own weight to print the portion of the design carried by the 40 block 6. In order to latch up those blocks which are to be held inoperative during any portion of the printing operation each block has associated therewith on each side of the bed 2, a latch 16 mounted on a rock shaft 19 45 and movable into engagement with a lug 20 carried by the slide carriers 14 to prevent the block from descending to print on the material as the cam 8 continues to rotate.

In the form of the invention illustrated 50 the latches 16 for each block are moved into the locking position shown in full lines in Figure 2 and into the released position shown in dotted lines by means of the rod 22 one end of which is secured to the lever 24 keyed 55 to the rock shaft 19 on which the latches are secured and the other end of which is secured to a three-armed crank 26. A turnbuckle 28 is carried by the rod 22 for adjusting its length.

60 The three arm crank 26 is provided with two arms 30 and 32 located on opposite sides of the shaft 34 on which the crank 26 is pivotally mounted. An operating rod 36 is connected to either of the arms 30 or 32 as desired. When the operating rod is connected

to the arm 32 as shown, upward movement of the rod causes the latch 16 to move to the left to release the block and allow it to print. However, when the operating rod 36 is connected to the arm 30 upward movement of the 70 rod causes the latch 16 to move to the right to hold the block in its raised or inoperative position. This construction of the latch operating mechanism renders it possible to latch up certain blocks and to release other blocks by similar actuating impulses or means. The operating rod is normally held in the lowered position by the weight 38, and is raised by means of the solenoid 40 acting on the core 42 secured to the bar 44 which is pivotally connected to the frame 18 and to which the lower end of the operating bar 36 is pivotally connected. 75

To provide for emergency operation of the latch 16 a hand lever 33 is mounted on the 80 shaft 34 and is rigidly secured to an arm 35 which may engage the crank 26 to move it in either direction against the force of the weight 38 or of the solenoid 40.

When not in use any block may be locked 85 in its raised or inoperative position by means of a pivoted stop 45 secured to the frame 18 adjacent to the lower end of the latch and movable into the dotted line position shown in Figure 2 to hold the latch in 90 engagement with the lug 20 so that the block will be held in its raised or inoperative position.

Each of the cams 8 which raise the printing blocks is formed with an arcuate portion 95 46, one end of which is provided with a high spot 48 which raises the slide carriers 14 and the lugs 20 above the projecting end of the latches 16 so that the latch can freely move into and out of locking position. When in 100 the locking position an undercut hook portion of the latch 16 engages beneath the lip 50 on the lug 20 and is held in engagement therewith, and against accidental displacement, by the weight of the slide 14 and related parts carried thereon. When the slide carriers 14 are held in the raised position by the latch 16 the roller 12 is held out of contact with the arcuate portion 46 of the cam 105 8 but is engaged by the high spot 48 on each revolution of the cam 8 to raise the slide carriers and lugs and permit the latch to be withdrawn by the weight 38 or by the solenoid 40. This device also serves as an accurate means of timing the operation of the latch, since the solenoid 40 or the weight 38 is not strong enough to release the latch until the slide 14 is lifted by the high spot on the cam. 110

In order to insure the positive movement 115 of the latch 16 during the short interval of time in which the slide is lifted by the high spot on the cam, the solenoid 40 is energized shortly before the arrival of the high spot 48 at the roller 12 and is kept energized at 120

least until the high spot of the cam is completely past the roller 12. This timing of the energizing of the solenoid 40 with the high spot 48 is effected by means of a cam 5 52 shown in Figures 3 and 6 mounted on the shaft 54 which rotates in timed relation to the rotation of the lifting cams 8. The cam 52 engages a switch operating member 56 for closing a switch 58 to permit an impulse to 10 be given to the solenoid 40.

Machines of the type described above may be employed in printing designs on material in any desired order. Such machines may be used to print roll goods, that is, material 15 on which the design is repeated at regular intervals throughout the length of the material or the machine may be arranged to print a series of complex designs on long webs of material to simulate rugs, the rugs 20 being cut apart after being printed on the web of material. In the simplest operation the design is repeated, for example, every 18 inches and the printing blocks are 18 inches wide. The material in this case will be advanced beneath the blocks in intermittent 25 steps of 18 inches each. Only one set of blocks is needed to print this type of design and each block in the set prints a portion of the design, usually a different color, on the 30 material. If the design be printed in five colors one set of five blocks may be employed and each block will apply its color to each 18 inch section of the material.

When the design is repeated every 36 inches 35 two sets of blocks are preferably employed, each block being 18 inches wide, each set of blocks printing only one-half of the design and each block in a set printing a portion of that half of the design. Such a design is 40 diagrammatically illustrated at the bottom of Figure 19. The sections marked A are printed with the desired colors by one set of blocks while the sections marked B are printed with the desired colors by another 45 set of blocks.

The separate portions of the design may be repeated at intervals spaced as desired, a set of blocks being employed for printing each portion of the design and each set of blocks 50 including at least one block for each color to be printed on that section of the material to which it corresponds.

In the printing of designs to simulate rugs the design may be divided into as many portions as the characteristics of the design may 55 require. For example, in printing rugs as illustrated in Figure 21 the sections marked A may be printed by a set of blocks which applies the field design and the side borders 60 of a rug and the sections of the material marked B may be printed by another set of blocks which applies oppositely faced nine inch end borders of two adjacent rugs which are later to be cut apart.

65 In a similar way the rug design may be

made up of three, four, five or any number of design portions which are to be printed on the material. The number of sets of blocks to be used is dependent upon the nature of the design to be printed. In printing complex 70 designs the number of sets of blocks is increased correspondingly since each set of blocks prints only one portion of the design. Figures 21 and 22 illustrate rug designs 75 printed with two and three sets of blocks respectively. When a machine of this type is operating on long webs of material it is desirable at times to allow an unprinted section 80 of the material to pass through the machine, as when a section of the material is imperfect or damaged. Furthermore, it is often desirable to change the entire order of the printing operations in order to repeat portions of the design without repeating the whole design or to print different designs on succeeding 85 rugs or sections of material. Thus, in order to attain the greatest flexibility of operation, the present invention includes mechanism by which the machine is controlled to cause the sets of blocks to print in any desired order or to be held inoperative for any desired length of time independently of any printing operations which have preceded or which are to follow and entirely at the 90 will of the operator. Such variations in the design and operation are effected in the construction illustrated by means of actuating or controlling mechanism for controlling the operation of the solenoids 40 which operate 95 the latches 16 to cause the printing blocks to be rendered operative and/or inoperative.

In the form of actuating or controlling mechanism illustrated, a controller 138 may be provided for each set of blocks used in printing the design. Thus in printing roll goods having the design illustrated in Figure 19, two sets of blocks are required and two controllers may be used each of which controllers regulates the operation of a different set of printing blocks. All of the controllers are substantially the same in construction but each is adjustable to cause the printing blocks to which it is connected to be operated to print on any desired section of the material. The controllers are located at the end of the machine near the point where the material passes from the supply roll onto the bed 2, so that the operator can watch for imperfections in the material and manipulate the control mechanism in time to change the printing order as required and can from the inspecting position determine exactly what printing 105 operation shall take place on each individual 110 18 inch section of the material before it enters the machine.

Each controller 138, as more clearly illustrated in Figures 7 and 8, is provided with a plurality of equally spaced contact brushes 70 arranged in a circle within the casing 72 and electrically connected to the solenoids 130

40 in a manner to be described. The brushes 70 are mounted on insulating blocks 74 carried by an insulating disc 76 secured to a stationary brass plate 78 mounted on the stationary shaft 80. A rotatable controller ring 82 extends adjacent the periphery of the plate 78 and is provided with a plurality of equally spaced holes 84 within which are located 5 slidable controller pins 86. Each controller pin 86 is formed with recesses 88 engaged by a spring-pressed ball 90 to hold the pin in either its projected or retracted position. The pins 86 are spaced apart the same distance as the brushes 70 and are moved intermittently about the disc 76 one space at a time and stopped in a position with relation to the brushes so that when in the projected position each pin is stopped momentarily in engagement with each of the contact brushes 10 70 in succession. The controller ring 82 is carried by the rotatable gear 92 which is formed of fiber or other insulating material secured to the flanged hub 94 which is rotatably mounted on the shaft 80.

25 The step by step rotation of the controller ring takes place in timed relation to the movement of the material over the bed of the machine so that each pin advances from one brush to the next with each advance of the material. This rotation is effected by the gear 96 mounted on shaft 98 which is rotated by the gear 100 and worm gear 102. The worm gears 102 for all of the controllers are mounted on a shaft 104 which is rotated intermittently in timed relation to the movement of the material over the bed of the machine by gear 106 which in turn is rotated by gear 108 and the ratchet 110, as clearly shown in Figures 8, 9, 10 and 11. The ratchet 110 is 30 intermittently driven by the pawl 112 which is carried on the upper end of the rod 114 and held in operative position on the ratchet by the radial arm 113. The lower end of the rod 114 is pivotally secured to the end of the lever 116 on which is also mounted a roller 118 bearing against the cam 120 which is secured to the shaft 54, which rotates in timed relation to the movement of the lifting cams 8 and to the operation of the material forwarding mechanism not shown.

35 This gear train and ratchet mechanism when operated cause the controller ring and the pins carried thereby to rotate step by step as the material is moved through the machine one space for each forward movement of the material. Thus the pins move into engagement with one brush after another as the ring rotates in perfectly timed relation as the successive sections of material move forward one section of the machine to the next adjacent section throughout the length of the machine. Each section of material takes up a position first under a block 40 6 and then in the space between adjacent

blocks so that when, for example, twenty-four blocks are used the material makes 47 forward steps through the machine. Therefore 47 separate pins and 47 brushes are required, but additional brushes and pins are advantageously provided in order to allow more flexible control, i. e., more ready adjustment of the device. The use of these additional brushes will be described later.

45 The brush 124 secured to and in electrical contact with the bolt 126 which is carried by but insulated from the casing 72 serves to connect the controller 82 into the solenoid operating circuit. Each of the brushes 70 is electrically connected to a pin jack connector 128 which may readily be connected, by means of a flexible conductor 132 having a pin jack terminal, to any one of a number of solenoid operating circuits. To avoid confusion we have shown in Figure 7 only two 50 of each connections, but it will be understood that in practice each of the brushes 70 is connected to a connector 128 in which one of the pin jacks may be inserted. The members 130 serve to connect the flexible conductors 132 55 to the conductor 134 which may lead directly to one of the solenoids 40. In practice, however, we find it advantageous, in order to reduce arcing between the pins and brushes, to have the circuits including the member 130 60 carry only a small current and the brushes and controller pins are connected to a relay solenoid 136 which, when actuated, completes the circuit through the solenoid 40 to actuate the latch 16. This arrangement is 65 shown in Figure 18, but in describing the operation of the parts and in the claims the circuits will, for the sake of brevity, be described and referred to as though the relay 136 was not employed.

70 A most important use of the invention is in the printing of designs to simulate rugs. Such designs are printed successively on long webs of the material and are afterward cut apart. However, in order to give a clear understanding of the mechanism, the arrangement and operation of the various elements will first be described as used in one of the simplest forms of printing; namely, the printing of roll material such as that illustrated in Figure 19. In printing this type of material two sets of blocks are employed and these blocks are actuated so that each block of each set prints on one section of material and is then held inoperative while the next sections of the material is under these blocks. The blocks again print on the next adjacent sections of material and again are latched up when the next succeeding sections are under these blocks. Thus the blocks indicated A' 75 110 A² A³ etc. which together print one portion of the design are caused to print the material successively on alternate sections marked "A" 115 on Figure 19, and the blocks B' B² B³ etc. are caused to print successively on the interme- 120 125 130

diate alternate sections of the material marked "B".

Ordinarily all of the blocks for printing one portion of the design are located adjacent to each other and those which print another portion of the material are located further down the machine. In this way the printing of one portion of the design is completed before the printing of another portion of the design is started. The blocks are therefore arranged so that the material passes the blocks in the order A' A² A³ etc. B' B² B³, etc. Other arrangements may be used as will be described later, in which, for example, some or all of the B blocks precede some or all of the A blocks in order of operation.

Two controllers are employed in printing this type of design. This arrangement is illustrated in Figure 19 in which the controller 138^a controls the operation of the blocks A' A² A³ etc. which print the portions of the design indicated by the letters A and the controller 138^b controls the operation of the blocks B' B² B³ etc. which print the portions of the design indicated by the letters B. The brush in the controller 138^a which is connected with the solenoid 40 associated with the printing block A' is indicated in Figure 19 by the numeral A'. Similarly the solenoids 40 which control the operation of the blocks A² A³ etc. and B' B² B³ etc. are connected to the correspondingly numbered brushes in the controllers 138^a and 138^b respectively.

The operating rods 36 which move the latches 16 for the printing blocks into and out of engagement with the lugs 20 are in this set-up each connected to the arms 32 of the three arm cranks 26 so that when the corresponding solenoids are energized the blocks will be rendered operative. The position of the operating rods 36 for both sets of blocks is the same.

The distance between the brushes 70 and between the pins 86 is such that each pin moves from one brush to the next with each advance of the web of material through the machine. Since, however, there are only half as many blocks as there are steps of the material through the machine the solenoids 40 will usually be connected to alternate brushes and the other brushes will then be disconnected by having no pin jack inserted into their terminal connectors. There is one conductor 132 in each controller connected to each of the solenoids 40 through the conductors 134 (see Figures 7 and 18) and each of these may be connected to any of the brushes by inserting its pin jack in the corresponding terminal connector. Thus by suitable arrangement of these pin jacks the printing blocks may be operated or held idle in any desired order. Or, if one or more of the blocks are not required in a set-up the corre-

sponding conductor 132 may be left unconnected to any brush.

When the various parts are arranged and adjusted for operation the material is moved through the machine in the direction of the arrow in intermittent steps of 18 inches each. The pins 86 carried by the controller rings are projected alternately from each controller ring so that as the rings rotate the projected pins in controller 138^a will engage the brushes A' A² A³ and the projected pins in controller 138^b will engage the brushes B' B² B³ etc. in the proper timed relation to cause each block to print on the alternate sections of material. In Figure 19 the pins which are projected are indicated by solid black dots and the pins which are not projected are indicated by circles. Thus, as the controller ring 82 in the controller 138^a is rotated the pin marked S' which corresponds to the section of material S' is brought into engagement with the brush indicated A', thereby causing the solenoid 40 associated with the block A' to be actuated to allow the block A' to print on the section of material S' which would be beneath that block at the same time that pin S' is in contact with brush A'. As the material is then advanced one 18-inch step forward the section of material S' would be moved into position between the blocks A' and A² and the section of material S² which is to be printed upon by blocks B' B² B³ etc. is brought beneath the block A'. The controller ring has been rotated one step forward simultaneously with the forward movement of the material so that the pin S' would then have moved forward out of engagement with the brush A' and into engagement with an idle brush between the brushes A' and A². Therefore the solenoid 40 associated with the block A' is not energized when the parts are in this position and the latch 16 holds the block A' inoperative so that the section S² is not printed upon by the block A'. When the material is then moved forward another 18 inches the section S' is brought beneath the block A² and the section S³ beneath the block A'. The simultaneous rotary movement of the controller ring brings the pin S' into engagement with the brush A² so that the solenoid 40 associated with the block A² is actuated to retract the latch 16 and allow the block A² to print another color on the section S' which was previously printed, e. g., with a different color by the block A'. At the same time the pin S³ has moved forward into engagement with the brush A', thereby making an electrical circuit to actuate the solenoid associated with the block A' to cause the latter to print its color upon the section S³ which has been moved into position beneath the block A'. In a similar way the material is advanced in steps of 18 inches each and the controller

ring 82 is rotated in similar steps to bring the projected pins S' S³ S⁵ etc. successively into engagement with each of the brushes A' A² A³ etc.

5 Since the brushes 70 and the pins 86 are arranged with respect to each other and the brushes are connected to the solenoids 40 of the various presses 5 in such manner that each pin advances from the brush connected 10 to the solenoid of one press to the brush connected with the solenoid of the next adjacent press with each two steps of the material through the machine, the setting of any pin determines whether one particular section 15 of the material will be printed upon or not, and if it is to be printed upon, what design will be printed upon it, according to the set-up of the controller mechanism, that is, according to which of the brushes are connected to the solenoids 40 and according to 20 which of the latches are connected through the arms 30 and which through the arms 32 to the solenoids 40.

The section S' when it has passed the printing block A⁵ in the sequence described in 25 connection with Figure 19, has had a different color applied thereto by each of the five printing blocks which have operated on that section of the material and the section S³ which is then located between the blocks A⁴ and A⁵ has received four colors and will move forward to receive the fifth color with the next advance of the material. The section S⁵ has at the same time just passed the block A³, 35 section S⁷ has just passed block A² and section S⁹ has just passed block A'

In the meantime, of course, the controller ring 82 of the controller 138^b has been advancing simultaneously with the controller ring of the controller 138^a. But in the controller ring of the controller 138^b only the pins S² S⁴ S⁶ S⁸ etc., corresponding to the sections S², S⁴, S⁶, etc. of the material have been pushed out. During the operation described above, while the pins S', S³, S⁵, etc. in the controller 138^a have been contacting with the brushes A' A² etc. the pins S², S⁴, S⁶, etc., of the controller 138^b have been passing brushes which are disconnected from the 50 solenoids 40. As the material advances further through the machine so as to bring the sections S², S⁴, S⁶, etc., of the material successively under the blocks B', B², B³, etc. the pins S², S⁴, S⁶, etc. contact with the 55 brushes B', B², B³, etc. to operate the solenoids 40 to release the blocks B', B², B³, etc. and permit them to print upon the sections S², S⁴, S⁶, etc., thereby completing the design. The pin S² which has been projected 60 from the controller ring 82 of the controller 138^b thus comes into engagement with the brush B' at the same time that the section S² is moved into position beneath the block B' so that the solenoid 40 associated 65 with the block B' will be energized to retract

the latch 16 and allow the block B' to print on the section between the printed sections S' and S³, that is on the section S², which had not been printed on by the blocks A' A² A³ etc. As the material is moved forward 70 additional steps the pin S² is moved into engagement with each of the brushes B² B³ etc. at the same time that the section of material S² is beneath the corresponding block. The pins S⁴, S⁶, etc. are advanced in a similar way as the material is moved forward 75 so that the blocks B' B² B³ etc. are each caused to print successively on each of the intermediate alternate sections of the material S⁴ S⁶ S⁸ S¹⁰, etc. Such printing operation may, of course, be continued indefinitely, the number of sections shown being taken only by way of example.

In the example illustrated the alternate pins S' S³ S⁵ are projected mechanically 85 from the controller 138^a, there being one idle or retracted pin between each projected pin. The pins S² S⁴ S⁶ etc. in the controller 138^b are similarly alternately projected but in 90 positions to be brought into engagement with the brushes B' B² B³ when the sections of material S² S⁴ S⁶ etc. have moved into position beneath the corresponding blocks B' B² B³ etc. The pins are automatically projected in this manner as long as it is desired 95 to continue the normal printing operation and are forced back into the retracted position at the end of a complete revolution of the controller ring 82 by a cam 150 illustrated in Figures 7, 8 and 13. 100

The projecting of the pins 86 from the controller ring 82 is effected by means of the spring pressed plunger 152 (Figures 3 to 6 and 12) which is engaged by the roller 154 carried by the arm 156 of the bell crank 164 pivoted on the shaft 104. A fiber pin 153 serves to insulate the plunger 152 from the pins 86. The crank is operated to move the plunger 152 forward to project the pins by means of a solenoid 160 which, when energized, acts upon the core 162 pivotally secured to the crank 164. The solenoid 160 which effects the projection of the pins 86, is controlled by an operating switch 170. A timing switch 163 is also included in the 110 circuit with the solenoid 160 to cause the solenoid to be operated only when the controller ring has moved into position to bring a pin in front of the plunger 152. The timing switch 163 is engaged by the timing cam 166 carried by the shaft 54 to which the cam 120 which moves the pawl 112 for the controller ring driving mechanism is secured. In this way the circuit through the solenoid 160 is only completed when the controller ring is in the proper position even though the switch 170 may be closed. 115

In Figure 7 the solenoid operated plunger 152 is shown in the position next adjacent to the first brush 70. This, of course, means 120

that, if the first brush is connected to the first solenoid, the pin to control the printing of each section is not projected until that section is about to pass under the first printing block. In some cases this arrangement may be desirable, while in other cases it may be more advantageous to control the treatment of each section while the material is farther away from the first block. In this latter case 10 the first one or more brushes 70 are left disconnected and a subsequent brush of the series is connected to the solenoid of the first block, all the other connections being moved correspondingly around the controller.

15 There is one solenoid 160 and associated operating mechanism therefore for each of the controller rings and a separate switch 170 controls the operation of the solenoid 160 for each controller ring to control the projection of the pins in each ring. The operation of the switches 170 therefore determines whether the pins 86 carried by each controller ring are to be projected and therefore determines whether either of the sets 20 of printing blocks is to print its portion of the design on each section of the material. The operation of the switches 170 may be controlled manually by the operator to cause any portion of the design to be printed upon 25 any desired section of the material or to cause any section of the material to pass through the machine without being printed.

30 Ordinarily, however, the design to be printed upon the material is such that the various portions of the design are repeated in a normal predetermined order. This normal printing of the parts of the design is effected automatically by means of a master cam made up of a plurality of separate parts 35 or cam elements each of which controls the operation of one of the switches 170.

35 The master cam used in printing the material illustrated in Figure 19 is made up of two cam elements 172^a and 172^b each of 40 which is provided with projections 176. The cam elements are secured to each other to rotate together and the projections on the cam element 172^a are circumferentially located between the projections upon the cam 45 element 172^b. As the master cam rotates the projections 176 are brought into engagement with levers 178 pivoted on the studs 180 and connected to the links 182 which actuate the levers 183 to close the switches 170.

50 The master cam is secured to and rotated by means of a ratchet 184 carried by the stud shaft 185 (Figures 14, 15 and 16), and a spring pressed latch 187 in the shaft 185 serves to hold the ratchet in position while 55 the pawl 186 is being retracted to engage another tooth. The ratchet 184 is rotated one step at a time with each forward movement of the material over the machine bed by means of a pawl 186 carried by the arm 188 which is secured to the shaft 190 which in turn is

journaled in the end of stud shaft 185 concentrically therewith. The shaft 190 is oscillated by the arm 192 connected to the rod 194, the lower end of which bears against the cam 196 mounted on the shaft 54 which 70 rotates in timed relation to the movement of the material over the bed of the machine. (See Figures 3 and 4.) The rod 194 is held in engagement with the cam 196 by means of the pivoted arm 200 and the spring 75 202. As the cam 196 rotates, therefore, the rod 194 is alternately raised and lowered so as to oscillate the pawl 186 and thereby rotate the ratchet 184 one tooth on each upward movement of the rod 194. 80

85 The alternate arrangement of the projections 176 on the cam elements 172^a and 172^b used in the operation illustrated in Figure 19, cause the switches 170 to be alternately actuated as the cam elements are rotated. That is, the projections 176 carried by the cam elements 172 are alternately brought into engagement with the levers 178, thereby closing the switches 170 and causing a pin 86 to be projected from the controller ring 90 82 of each controller 138 with each forward movement of the material, first from 138^a and then 138^b, one at each forward movement. This arrangement of operating mechanism causes the pins 86 to be projected in the respective controller rings at the proper times and in the proper positions to cause the solenoids to be actuated to permit the printing blocks A' A² A³ and B' B² B³ to print their 95 respective portions of the design upon the alternate sections of the material as illustrated in Figure 19.

100 In printing material with the arrangement of mechanism described it may be desirable at times to allow an unprinted section of material to pass through the machine. For this purpose means are provided for disconnecting the driving connection consisting of a ratchet 184 and pawl 186 and at the same time breaking the pin-setting circuit for each controller. Each of the printing blocks is thereby successively held in the inoperative position until the desired length of unprinted material has passed. When it is desired to start printing the design again 105 the pawl 186 is again moved into engagement with the ratchet 184 and the circuits including the pin-setting solenoids closed. The master cam then rotates in the normal manner to project the pins and continue the 110 printing operation as before.

115 In order to effect this release of the driving connections at the proper time so as to prevent the projecting of pins from the controller rings in normal order, a member 210 120 is provided, as shown in Figures 14, 16 and 17, which may be moved to disconnect the pawl 186 from the ratchet 184. The normal position of the member 210 is shown in Figure 16 with the member in engagement with 125 130

the adjustable stop 212. When it is desired to pass an unprinted section of material through the machine a handle 214 is moved in a clockwise direction as indicated by the arrow. In order to prevent the pawl 186 from being disconnected from the teeth of the ratchet 184 during an upward stroke of the pawl and while the master cam is being rotated, this handle 214 is not connected directly to the member 210 but is connected to the shaft 216 so that clockwise movement of the handle causes the shaft 216 to rotate and throw the weight 218 from the full line position shown in Figure 17, to the dotted line position. The member 219 is also fixed on the shaft 216, so that it is moved by the handle 214 and the weight 218 from the full line position shown in Figure 17, where its ear 220 engages the stud 222, to the dotted line position in which its other ear 224 engages the stud. In this latter position the force of the weight 218 bears through the member 219 against the stud 222, and since this stud is carried on the extension 226 of the arm 228 the force of the weight 218 urges the arm 228 away from the oscillating shaft 190 against which the roller 230 carried by the arm 228 normally bears. A guard 232 which oscillates with the shaft 190 engages the roller 230 to prevent it from moving away from the shaft 190 except when the pawl 186 is substantially at the limit of its downward movement. The member 210 is secured on the tubular shaft 234 to which the arm 228 is also secured and therefore movement of the arm 228 away from the shaft 190 under the influence of the weight 218 carries the member 210 also in a clockwise direction and into engagement with the roller 236 carried by the pawl 186, and against the adjustable stop 238. This movement of the member 210 causes the pawl 186 to be rocked about its pivot 240 and out of engagement with the teeth of the ratchet 184; but such movement cannot take place until the pawl is at the bottom of its stroke at which time the roller 230 is released from the guard 232. In this disconnected position the pawl 186 may continue to oscillate, its roller 236 riding over the arm 210 and holding it away from the ratchet 184.

The member 210 when moved clockwise to retract the pawl 186 allows the arm 242 carrying the roller 244 to move to the left under the influence of the spring 246. This movement of the arm 242 opens a switch 248 in the circuit to the pin-setting solenoid 160 so that the circuit is broken and the solenoid 160 is not energized even though the switch 170 may be closed by a projection 176.

As the purpose of the handle 214 and the linkage just described is to run a portion of the material through the machine without printing upon it, the opening of the switch 248 is only desirable so far as it applies to the

control of printing heads which are latched up until released by the solenoids 40. If, on the contrary, the printing heads are normally free and are latched up by positive action of the solenoids 40 it is necessary to close the circuit instead of opening it. In this case, the switch 248 may be arranged to close circuits for the controllers connected with certain printing heads and open the circuit for others or to close or to open all circuits depending upon the arrangement of the latches on the printing heads. Instead of this arrangement, certain of the pin-setting circuits may be wired around the switches 248, e. g., by means of conductors 250 in the panel 252, as shown in Figure 21. With this latter arrangement it is necessary to have the corresponding switch 170 closed, so that if a projection 176 is not already in position to close the switch, the operator must turn the master cam 172 by means of the hand wheel 260 until it is in a position to close the required switch or switches.

In the present example, the conductors 253 connect the switches 170 and the conductors 254 through the switch 248 to the line so that when the pawl is disengaged and with either of the switches 170 closed by a projection 176, the solenoid 160 associated with such switch 170 will not be energized when the timing switch 163 is closed by cam 166, and thus none of the pins 86 will be projected in the rings 82.

In Figure 24 is shown diagrammatically the sequence in which the various parts operate. Vertical measurements represent space displacements, horizontal measurements indicate time. The solid lines 4 indicate the movement of the material, the lines formed of long dashes 8 indicate the vertical movement imparted to the blocks by the cam 8, the dot-dash lines 186 indicate the movement of the pawl 186, the short-dash lines 82 indicate the movement of the controller so as to carry the pins from contact with one brush 70 into contact with the next, the dash-star lines 163 indicate the movement of the timing switch 163, and the zig-zag lines 58 indicate the movement of the timing switch 58. Beginning with the movement of the material 4, as indicated by the rise in the line 4 from 277^a the material is moved from one position to the next and reaches the new position at the point 268^a. At this point the timing switch 163 begins to close and at the point 269^a the switch is closed and the solenoid 170 is energized to project a pin from the controller 82. At the point 270^a the timing switch 163 is open so that the solenoid 170 is no longer energized and its pin-setting plunger is withdrawn from the rotor 82. The rotor 82 then begins to move and at the point 271^a its movement is complete so that each pin has been advanced from one brush 70 to the next. In the meantime at the point 272^a

the switch 248 is closed so that the circuit to the pin-setting solenoid 160 is closed and the solenoid 160 is energized to project a pin from the controller 82. At the point 273^a the switch 248 is open so that the circuit to the pin-setting solenoid 160 is broken and the solenoid 160 is not energized even though the switch 170 may be closed by a projection 176.

the pawl 186 has completed a downward stroke and has started on an upward stroke in which it will engage the ratchet 184 to move the master cam 172 to its next position. 5 Shortly after the point 272^a, for example, at 273^a, the timing switch 58 and the cam 8 begin to move almost at the same time. The timing switch, however, is closed before and remains closed after the point 274^a, at which 10 point the high spot on the cam 8 is beneath the cam follower 12, so that the slide 14 and its lug 20 is lifted free from the latches 16. When this occurs, i. e., when the lug 20 is lifted free of the latch 16, the solenoid 40 is 15 energized at 280^a through the timing switch 58 and the latch 16 therefore moves into or out of engagement with the lug 20 according to whether the solenoid is connected through the arm 30 or the arm 32. The period during 20 which the timing switch 58 is closed, as shown by the flat part 280 of the line 58 in Figure 24, substantially overlaps on both sides the period during which the lug 20 is lifted above the latch 16. As the cam 8 rotates to the 25 slope beginning at the point 275^a the printing head, that is, the slide 14 and the printing block 6 are allowed to descend until the printing contact takes place at the point 272^b. In the meantime, at the point 277^b and while 30 the printing head has been held up by the cam 8, the web of material 4 has moved forward to the next position and this movement has been completed at the point 268^b. In the meantime, also, the upward movement of the 35 pawl 186 has been completed at the point 279^b and the pawl again begins to move down toward the point 272^b.

It will be understood, of course, that the sequence illustrated by the diagram of Figure 24 is exemplary only and represents a preferred embodiment but that the periods represented in this figure may be varied to a greater or less extent with respect to each other without departing from the spirit and 40 scope of our invention. It is this sequence of events, however, that has been used as a preferred embodiment in the examples which are described herein.

Following this diagram through briefly 45 with a simple change from automatic to manual control as, for example, is illustrated in Figure 19 at the section S¹². With the section S¹² moving into the position two steps before its position under the block A' as indicated from 277^a to 268^a the operator has decided to leave the section S¹² blank. He therefore throws the handle 214 over to the non-printing position. Before the pawl 186 is disconnected it will have brought the projection 50 176 on the master cam 172^a into the position at 279^a to hold the lever 178 in its closed circuit position. The timing switch 163 will be closed at the point 269^a, thus projecting a pin in the controller 138^a. This pin will move 55 into position to contact with the brush A' at

the point 271^a. The timing switch 58 closes at the point 280^a to close a circuit through the brush A' to the solenoid 40 associated with the head A' and thus to retract the latch 16 at point 274^a to permit the printing of the block A' at the point 272^b on the section S¹¹ which has moved into position under the block A' at the point 268^b. At the point 272^a the roller 230 is released from the guard 232 and the weight 218 causes the shaft 238 and its 60 arm 210 to rotate so as to disengage the pawl 186 from the ratchet 184. Consequently during the following upstroke of the pawl 186 it will be disengaged from the ratchet and the cam 172 will not be moved but will remain in position with a projection 176 on the master cam 172^a holding its corresponding switch 170 closed. The movement of the shaft 238 and the arm 210 also causes the switch 248 to 65 open and thus prevents the energizing of the solenoid 160 at the following point 269^b and prevents the projecting of another pin in the controller 138^a at that point. In the meantime and while the section S¹¹ has been moved under the block A' the section S¹² has 70 advanced to the position next to the block A'. At the point 271^b the pin which remains retracted because the switch 248 was open at the point 269^b is advanced to the position for controlling the operation of the block A'. Thus, when the cam 8 turns to the point 274^b the solenoid 40 will not be energized since no pin has been projected to contact with the corresponding controller brush 70, and consequently the printing head, that is, the slide 14 and the printing block 6 will remain latched up during the subsequent printing period beginning at 272^b. In the meantime the section S¹² has moved between the points 75 277^b and 268^c into the printing position under the block A' but as already stated, it will not be printed upon because the printing head is held up by the latch 16.

The cycle of operations with the pawl 186 moving idly and the switch 248 preventing 80 the projecting of pins at the points 269, consequently preventing the energizing of the solenoids 40 at the following points 280 to unlatch the printing heads continues until the operator decides again to print on a section 85 of material, for example, section S¹⁵. Assuming again that section S¹⁵ is two steps removed from the position under the block A', the handle 214 is thrown back. This may be done either just before, during or just 90 after the movement of the material into this position but must be done before the point 272 as at 277^a. At the point 272^a the roller 230 enters under the guard 232 and the shaft 238 with its arm 210 rotates so that the pawl 186 95 is released and the switch 248 closed. On the following upward stroke of the pawl 186 it engages the ratchet 184 and moves the master cam 172^b into position to close the switch 100 170. At the point 274^a during this upward 105

stroke of the pawl 186 there still has been no pin set in the controller 138^a so that nothing will be printed on section S¹⁴ as at 272^b. The material begins to move again during this stroke so that the section S¹⁵ is brought into position next to the block A'. At the following point 269^b the switch 248 and the switch 170 are both closed so that a pin is projected in the controller 138^b. At the point 271, as at 271^b this pin is moved into contact with the brush in controller 138^b, corresponding to the brush A' in controller 138^a. Since this brush in controller 138^b is an idle brush and since no pin has been projected in controller 138^a the section S¹⁵ will not be printed upon by the blocks A' A² A³ etc. But this projected pin in controller 138^b will reach brush B' at a later point 272 to release the printing head B' at the corresponding point 274 and the section S¹⁵ will move under this printing head B' at a corresponding time 268.

It will thus be seen that the operator must decide whether a section is or is not to be printed upon when that section is at least two steps removed from the first printing position. If, however, he had not decided until the material was in the position next to the printing position that a section should not be printed upon, he could still avoid printing by the use of the emergency button 262. By depressing this button during the period between 268^b and 270^b the pin setting circuit would be opened and the solenoid 160 would not be energized to push out the pin at 269^b. This, however, would not have prevented the movement of the pawl 186 in engagement with the ratchet 184 and it would therefore have been necessary to reset the master cam 172 if a design B were to be printed on the following section.

This resetting of the cam by moving it forward or back one or more steps could be done at any time prior to the next following point 268, i. e., at 268^c, since at that time the projection 176 would have to be on the lever 178 in order that both the switch 170 and the timing switch 163 would be closed at the same time. Similarly, if, instead of printing a blank it is desired to print two sections, for example two B sections as at S¹⁷ and S¹⁸ side by side, the operator may decide at any time just before or during the time that the section S¹⁸ moves into the position next preceding that under the block A'. At any time from the point 270^a just before the section S¹⁸ moves into the position preceding that under the block A' and before the point 268^b in such position, the master cam may be turned by means of the hand wheel 260 the angular distance of one ratchet tooth, thus moving it forward past the intermediate A setting to the next B setting or back again to the same B setting. Thus, when the timing switch is closed at the point 269, as at 269^b, the projection 176 on the master cam

172^b will be in position to close the switch 170 and thus the design B will be repeated without an intermediate A design.

If the last printed section S¹¹ had had a B design, or if the operator had wished to begin again with an A design he would then have reset the cam in the above described manner at any time during the disengagement of the pawl 186 or on its following up stroke.

In this way the operator may move the master cam at any time to bring a projection on any of the cam elements into engagement with the associated lever 178 so that he may cause the portions of the design to be printed in any desired order or by throwing the handle 214 he may cause the blocks to be held inoperative as desired without interrupting the operation of the machine.

The design illustrated in Figure 19 may be printed with the mechanism described using a number of different adjustments. An adjustment and arrangement of the parts which is somewhat simpler and therefore to be preferred to the arrangement above described is shown in Figure 20 as follows: The operating rods 36 which are associated with the latches for the blocks B' B² B³, etc. are connected to the arm 32 of the crank 26 as described so that when the solenoids 40 associated therewith are energized, the latches 16 will be moved out of engagement with the lugs 20 and the blocks B' B² B³ allowed to print. The operating rods associated with the blocks A' A² A³ are connected to the opposite arms 30 of the cranks 26 so that when the solenoids associated therewith are energized, the latches 16 will be moved into engagement with the lugs 20 to hold the blocks A' A² A³ in their raised or inoperative positions.

With this adjustment of the operating rods only one master cam element is necessary for continuous operation. It is advantageous, however, to use two controller mechanisms, as shown in Figure 20, as otherwise either A or B will print when a pin is projected and the other when no pin is projected and it is not possible to use the handle 214 to stop the printing on particular sections of the material in the manner above described.

When a single controller is used, the cam element 172 is similar to the cam elements employed in the last described arrangement. When a pin is projected one design will be printed and the blocks for the other design locked up while that section is under them. If a pin is not projected the blocks which are normally unlocked will print and those that are normally locked up will remain so.

When two controllers are used the blocks printing one design may be locked up and those printing the other design unlocked. With this arrangement also the cams are similar in that they will have one projection 176

for each two teeth on the ratchet 184 by which the master cam is rotated. In this case, however, each projection 176 may operate both of the levers 178 associated with the controllers 5 138^a and 138^b to simultaneously project a pin in each of the controllers or as an alternative one switch 170 may be used to control the operation of both solenoids 160.

As the master cam rotates alternate pins 10 are projected in both of the controller rings; and, as the pins are brought successively into engagement with the brushes A' A² A³ in the controller 138^a, the solenoid 40 is energized. The latches 16 are thus made to engage their printing heads and the blocks A' 15 A² A³ are held inoperative over the sections of material S² S⁴ S⁶, etc. as in the previous arrangement of the parts. However, when the projected pins in the controller 138^b engage the brushes B' B² B³ the latches 16 are 20 retracted from the heads which carry the blocks B' B² B³ and they are allowed to print. Since the same pins are projected in each controller, the blocks governed by the controller 138^b will print while those governed by 25 138^a are idle or vice versa according to whether pins or spaces are aligned with the brushes.

With this arrangement of parts it is necessary 30 to connect the conductor 253 which is connected with the pin setting solenoid 160 for the controller 138^b through the switch 248 in the panel 252. However, the conductors 253 and 254 connected to the pin-setting solenoid for the controller 138^a connect the switch 170 directly to the solenoid.

When it is desired to pass a blank portion 40 of the material through the machine with this set-up, the handle 214 is moved clockwise and the switch 248 is opened so that no pins are projected in the controller 138^b and therefore the blocks B' B² B³ etc. do not print on the material, the operator rotates the master cam until one of the projections 176 on the 45 master cam 172^a is in engagement with the lever 178 so that the switch 170 remains closed, the pin-setting solenoid 160 connected directly to the switch 170 becomes energized with each closing of switch 163 and thus a pin is projected in the controller 138^a with each forward movement of the material and the blocks A' A² A³ etc. are held 50 inoperative while the blank section of material passes beneath. To start the printing operation again the handle 214 is moved counter clockwise the pawl 186 is again brought into engagement with the teeth of the ratchet 184 and the switch 248 is closed and the printing operation thus resumed. In 55 printing the sections in an order other than that for which the master cam is designed the method of printing adjacent sections of the material with the same portion of the design is the same as that described in the previous arrangement of parts.

Another adjustment of the mechanism using only one controller for printing this type of design is as follows: The blocks A' 70 A² A³ etc. are connected to the first, third, fifth and following odd brushes on the controller, and the blocks B' B² B³ etc. are connected to the third brush following the last brush used for blocks A' A² A³ and alternate succeeding, i. e. even numbered, brushes on the controller. One master cam element is employed as in the previous arrangement. The arrangement of all of the operating rods 36 is the same, so that when any one of the solenoids 40 is energized the latch 16 is retracted and the corresponding block allowed 80 to print.

In operation the alternately projected pins move over the brushes so as to engage first the brushes A' A² A³, etc., then the brushes B' B² B³, etc. Thus, the solenoids associated with each set of blocks are alternately energized one set at each forward movement of the material, and therefore print on the alternate sections of material. The blocks A' A² A³ etc. being connected to the odd 90 brushes on the controller print on the odd sections of material S' S³ S⁵ etc. whereas the blocks B' B² B³ etc. being connected to the even brushes on the controller, print on the 95 even sections S² S⁴ S⁶ etc.

In printing a blank section of material the pawl 186 is retracted and the switch 248 opened to prevent any pins from being projected as in the first arrangement described. However, the arrangement of parts is not as 100 flexible as the first arrangement since the printing order cannot be varied except by manual manipulation of the latches 16.

The foregoing alternative examples are given to illustrate the possibility of effecting desired results by a number of arrangements and adjustments each of which may be of particular advantage for some particular design. This great flexibility of adjustment is of the greatest advantage in printing more complicated designs and particularly in printing designs to simulate rugs. The printing of rugs on this type of printing machine has presented heretofore many difficulties due to the inflexibility of the adjustments and arrangements. However, the present invention because of its extremely flexible control is particularly adapted to effect a large number of such adjustments so that rug designs or other designs of the greatest complexity may be printed and the sequence or design varied at will. Examples of such arrangements and adjustments will be given, but in each instance it may be possible to print the design illustrated by making other adjustments or arrangements of the various parts than those particularly described.

In printing one of the simplest types of rugs such as that illustrated in Figure 21 two 130

sets of printing blocks are employed, the printing blocks indicated $A' A^2 A^3$ etc. print the field and side border sections "A" of the rugs and the printing blocks indicated $B' B^2 B^3$ etc. print the sections "B" carrying two oppositely faced end borders 9 inches wide which are afterwards cut between these end borders to form the separate rugs. In printing this design as a 9' x 12' rug, that is, on eight sections of material, each 18" long and 9' wide, the field blocks $A' A^2 A^3$ etc. are allowed to print on seven successive sections of material after which they are successively held inoperative while one unprinted section in which the end borders are to be printed is passed beneath them. Conversely the border blocks $B' B^2 B^3$ etc. are held inoperative while seven sections of material printed by the field blocks are passed beneath them and are then successively allowed to print on one section of material.

Two controllers 138^a and 138^b are used in printing this type of rug. However, only one master cam element 172^a and one switch 170 are employed and this switch actuates both solenoids 160 associated with the controllers 138^a and 138^b and therefore controls the pin-setting operation in each of the controllers. The master cam has only one projection 176 and is rotated by means of a ratchet which when the normal rug is 12 feet long, has eight teeth one for each section in the normal completed design.

The operating rods 36 which move to actuate the latches 16 controlling the operation of the printing blocks are connected so that the printing blocks $A' A^2 A^3$ etc. which print the field and side border sections "A" of the design are held in the inoperative position when the solenoids associated therewith are actuated. The operating rods 36 associated with the blocks $B' B^2 B^3$ which print the end border sections "B" of the design are connected so that when the corresponding solenoids are energized the latches 16 are retracted and the blocks $B' B^2 B^3$ etc. are allowed to print.

The solenoid 40 associated with the block A' is connected to any desired brush A, in the controller 138^a. The succeeding blocks $A^2 A^3 A^4 A^5$ are connected to the alternate succeeding brushes $A^2 A^3 A^4 A^5$. The solenoid associated with the block B' is connected to the brush B' in the controller 138^b corresponding to the second brush after A^5 in the controller 138^a and the succeeding blocks $B^2 B^3 B^4 B^5$ are connected to the alternate succeeding brushes $B^2 B^3 B^4 B^5$. In other words, the brush B' in the controller 138^b is chosen as that brush which a pin, in controller 138^b simultaneously projected with a pin in controller 138^a, will reach two movements of the material later than the time when the pin simultaneously projected in controller 138^a

reaches the brush associated with the last printing block in the "A" series.

The blocks for the different designs need not be separated as shown in the drawings. Thus it may in some cases be desirable to print the main background of both designs before filling in the detail of other colors, and in this case the block B' would be put on the printing head 14 either following or preceding the head carrying the block A. With this arrangement the solenoid 40 associated with the block B' would be connected to a brush in the controller 138^b which would be reached by a pin two steps after (or before, if the block B' precedes A') the solenoid associated with the block A' is actuated by a pin in controller 138^a. Similarly any desired arrangement of the blocks 6 may be made and the associated solenoids 40 connected to brushes in the controllers 138 so that they may be actuated at the proper time by pins set in the order determined by the cam 172^a.

The conductors 253 and 254 which connect the switch 170 to the pin-projecting solenoids 160 are connected through the panel 252. Those conductors which are connected with the pin-setting solenoid for the controller 138^b, which controls the operation of the end border printing blocks $B' B^2 B^3$ etc. are connected through the switch 248 so that when the switch is opened by movement of the handle 214 to retract the pawl 186 the circuit through the conductors 253 and 254 connected with the pin-setting solenoid 160 will be broken. The conductors 253 and 254 connected to the pin-setting solenoid 160 for the controller 138^a which controls the operation of the field and side border printing blocks $A' A^2 A^3$ etc. are directly connected so that movement of the handle 214 to retract the pawl will not break the circuit through these conductors.

The operation of the mechanism when so arranged is as follows: At the beginning of the printing the operator sets the master cam by means of the hand wheel 260 so that the projection 176 engages the lever 178 at the beginning of the first down stroke of the pawl 186. A pin is projected in each of the controllers 138 at the center of the down stroke. The pin in the controller 138^a will prevent the printing of the blocks A' , $A^2 A^3$, etc., as this first section of the material passes beneath them, but when this section of the material reaches the block B' and the successive blocks $B^2 B^3$, etc., the corresponding pin in the controller 138^b will unlatch the printing heads and cause the printing of these blocks; thus an end border is therefore printed on the first section. As the master cam rotates no pins are projected in either controller ring until the projection 176 again engages the lever 178. During this period of operation the material is moved forward in successive steps of 18 inches each and the master cam is ro-

tated $\frac{1}{8}$ of a revolution by the pawl 186 with each forward movement of the material. Since no pins are projected in the controllers 138 during this portion of the operation the 5 solenoids 40 associated with the blocks A' A² A³ are not energized and therefore the latch 16 for each of these blocks is held in the retracted position so that each of the blocks is allowed to print on adjacent sections 10 of the material. The solenoids 40 associated with the blocks B' B² B³ also are not energized and therefore the latches 16 associated with these blocks hold the blocks in the raised or inoperative position so that they do not 15 print on the sections of material passing beneath the same.

When the master cam is rotated to bring the projection 176 again into engagement with the lever 178 one pin is projected in each 20 of the controllers 138^a and 138^b so that as the projected pins pass over the brushes A' A² A³ and B' B² B³ in succession the solenoids associated with the corresponding printing blocks are energized. This causes each of 25 the printing blocks A' A² A³ etc. successively to be held inoperative over one section of material and the printing blocks B' B² B³ to be successively allowed to print on this section of material as it is moved into position beneath 30 each block in turn. Thus, as the material passes through the machine the printing blocks A' A² A³ etc. are each caused to print on seven successive sections of material and are then successively held inoperative while 35 over one section of material as the single pin projected in the controller 138^a by the single projection 176 on the master cam passes over each of the brushes A' A² A³ in succession. In a similar way the blocks B' B² B³ are each 40 held inoperative during seven successive forward movements of the material and are then successively allowed to print on the unprinted section of material as the single pin projected in the controller 138^b by the single projection 176 on the master cam passes over 45 each of the brushes B' B² B³ in succession.

During the normal operation in printing these rugs the operator does not need to adjust the master cam in any respect. However, if a bad spot should appear in the material or if he should wish to pass an unprinted section of the material through the machine for any other reason, the operator rotates the master cam ahead, in a counter-clockwise direction, so that the projection 176 55 engages the lever 178 when the center of the down stroke of the pawl 186 is reached, thus causing a pin to be projected in each controller to print a border to finish off the rug of which 60 the field portion has just been printed. He also moves the handle 214 at any time before the bottom of the same stroke of the pawl 186 and after the start of the preceding up-stroke. The pawl 186 when it reaches the 65 bottom of its stroke will be disengaged by the

force of the weight 218 which is released at that point from the guard 232, thus opening the switch 248 and breaking the circuit including the pin-projecting solenoid 160 for the controller 138^b. One pin in each of the controllers 138^a and 138^b for the end border section B, however, has already been projected at the center of the down-stroke of the pawl 186, so that the opening of the switch 248, does not interfere with the printing of that section. Since the opening of the switch 248 prevents the projecting of additional pins in the controller 138^b none of the blocks B' B² etc. will print after the pin for the end section has passed the brushes associated therewith. Since the cam 172^a has stopped with its projection 176 depressing the lever 178, the switch 170 is closed; and since the solenoid 160 of the controller 138^b is wired direct to the switch 170, all pins will be projected therein as they pass the plunger 152, and the blocks A' A² etc. will be held latched up while that part of the material following the end border section passes under them. As long as the handle 214 is left in the right-hand position the master cam is not rotated and the situation just described continues, and each section of the material which enters the machine during this time is destined to come through unprinted. 95

When the imperfect portion of the material has passed and it is desired to start the printing operation again the handle 214 is moved to the left to bring the pawl 186 again into engagement with the teeth of the ratchet 184 and to close the circuit through the switch 248. The following stroke of the pawl 186 would in the normal course of its operation move the projection 176 away from the lever 178 before the timing switch 163 was closed to actuate the solenoid 160 and project a pin. Therefore, in order to start a new rug design with an end border it is necessary for the operator to manually reset the master cam to bring the projection 176 back onto the lever 178 before the timing switch 163 is closed. At the next stroke of the pawl 186 the ratchet 184 and the master cam are rotated thereby, so as to move the projection 176 past the lever 178, and the printing operation continues its normal course. 110

Any rug section can, of course, be finished off prematurely by manually rotating the master cam to print an end border section as above described, whether the following section is to be a blank or another rug. This procedure may be used to make a desired number of smaller rugs or to bring the end of a rug at a point where it is desired to cut the web, e. g. for convenience in drying, or it may be used to make the end of the rug come as near as possible to the end of a roll of material being printed. Obviously also the master cam can be manually moved backward one or more steps or forward past the 125 130

projection 176 so as to avoid printing an end border at the regular time, and in this manner longer rugs can be printed. By moving the ratchet forward 1, 2, 3, 4, 5, 6 or 7 teeth, 7, 5 6, 5, 4, 3, 2, or 1 additional field sections will be printed before the next end border. Or the cam can merely be moved one step past the projection 176 and then again moved to bring the projection 176 into position when 10 the desired number of field sections have been printed. Rugs of any desired length may be printed in this manner regardless of the setting of the machine.

This type of rug may also be printed with 15 only one controller although certain of the advantages of flexibility in operation are sacrificed when only one controller is employed. For example, the master cam may contain only one projection as in the arrangement 20 just described and the solenoids associated with the blocks B' B² B³ etc. connected to the brushes following the brushes to which the solenoids associated with the blocks A' A² A³ are connected. The arrangement of 25 the operating arms which move the latches 16 into and out of engagement with the lugs 20 is the same as that described in the previous arrangement. Thus, as the pin projected in the controller when the projection 176 engages the lever 178 passes over each of the brushes to which the solenoids are connected in succession the blocks A' A² A³ etc. are held inoperative, whereas the blocks B' B² 30 B³ etc. are released to print.

In printing the design of rug illustrated 35 in Figure 22 three sets of blocks are employed, the first set indicated A' A² A³ etc. having that portion of the design for printing the field and side border sections of the design, the second group of blocks indicated B' B² B³ having one border of the design facing in one direction and the third group of blocks indicated C' C² C³ etc. having the other end border of the design facing in the opposite 40 direction from that carried by the blocks B' B² B³. The control of the printing blocks in this case is such that an end border is first printed by the blocks C' C² C³ etc., the blocks A' A² A³ etc. are then allowed to print on six 45 successive sections of material and then successively held inoperative while two unprinted sections pass. The blocks B' B² B³ etc. are held inoperative while seven sections of material pass and are then successively allowed to print on the section of material following the last section printed by the blocks A' A² A³ etc. The blocks C' C² C³ etc. are held inoperative while seven sections of 50 material pass and are then successively allowed to print on the section of material following the section printed by the blocks B' B² B³ etc.

In printing rugs having designs of this character three controllers may be employed, the controller 138^a being associated with the

group of printing blocks indicated A' A² A³ etc., the controller 138^b being associated with the group of blocks B' B² B³ etc. and controller 138^c being associated with blocks C' C² C³ etc. In the arrangement shown in Figure 22, the operating rods 36 associated with the blocks A' A² A³ for printing the field and side border sections of the design are connected so that when the solenoids associated therewith are energized the latches 16 are moved into engagement with the lugs 20 to hold the blocks in the raised or inoperative position. The operating rods 36 associated with the groups of blocks B' B² B³ etc. and C' C² C³ etc. are connected so that when the corresponding solenoids 40 are energized the latches 16 are moved out of engagement with the lugs 20 to permit the corresponding blocks to print. In this set-up three cam elements 172^a, 172^b and 172^c are employed in the master cam. Each of the cam elements 172^b and 172^c is provided with one projection 176 and the cam elements are secured to rotate together with the projection 176 on one spaced circumferentially from the projection 172^a on the other an angular distance corresponding to one ratchet tooth. The cam element 172^a is provided with two projections 176 spaced circumferentially apart the angular distance corresponding to one ratchet tooth, 90 each projection 176 being aligned with a projection 176 on the cam elements 172^b and 172^c. The ratchet as before is provided with eight teeth. The conductors 253 for each of the pin-setting solenoids 160 are connected with 100 the panel 252. The conductors 253 connected to the pin-setting solenoid for the controller 138^a is connected to the switch 170 so that when that switch is closed by a projection 176 on the master cam element 172^a it will cause 105 a pin to be projected in the controller 138^a. The conductor 253 connected to the pin-setting solenoid 160 for the controller 138^b is connected through the switch 248 so as to be actuated by the master cam element 172^b. The 110 pin-setting solenoid for the controller 138^c is connected to the switch 170 actuated by the master cam element 172^c. Thus the controller 138^a has a pin projected therein for each pin projected in either of the controllers 138^b 115 and 138^c.

In printing rugs having designs such as that illustrated with the arrangement described, rotation of the master cam, starting from the position for beginning a rug design, causes the projections 176 carried by the cam elements 172^a and 172^c to depress the levers 178 to cause a pin to be projected in each of the controllers 138^a and 138^c. As the master cam continues to rotate no pins are 120 projected in any of the controllers until the projections 176 carried by the master cam elements 172^a and 172^b engage the levers 178. A pin is then projected in each of the controllers 138^a and 138^b and with the next for 125 130

ward movement of the material and the next step in the rotation of the master cam the projections 176 carried by the cam elements 172^a and 172^c are again brought into engagement with the levers 178 so that pins are projected in each of the controllers 138^a and 138^c. Thus two pins are projected in controller 138^a after which six retracted pins pass, a pin corresponding to the first pin in controller 138^a is projected in controller 138^b, after which seven retracted pins pass; and similarly a pin is projected in controller 138^c corresponding to the second projected pin in controller 138^a, after which seven retracted pins pass.

By this arrangement the printing blocks A' A² A³ etc. print on each of the sections of the material when no pin is projected in controller 138^a. However, when the controller pins projected by the rotation of the cam elements 172^a and 172^c are brought into engagement with the brushes A' A² A³ and C' C² C³, the printing blocks A' A² A³ etc. are successively held inoperative and the printing blocks C' C² C³ are successively allowed to print.

When it is desired to pass an unprinted section of the material through the machine, the handle 214 is thrown over and the hand wheel 260 turned, as described above in connection with Figure 21. In this case, however, the projections 176 are not in the same position, and which projection is to be engaged with the lever 178 depends upon which switch 170 has been connected through the switch 248. In the drawings the switch operated by the cam 172^b is shown connected to the switch 248, and this is the more advantageous arrangement since a blank section will ordinarily follow an end border B and the master cam will stop with the projections 176 of the cams 172^a and 172^b on the levers 178. In this circuit, however, the switch 248 opens and thus prevents the projecting of pins in the controller 138^b. The connection across the panel to the solenoid 160 of the controller 138^a permits the projecting of pins in the controller 138^a for each section so long as the switch 170 remains closed. If the switch 248 were connected into the circuit of the solenoid for the controller 138^b it would then be necessary to turn the hand wheel 260 to depress the lever 178 associated with the cam 172^b and then to turn it back again when regular operation is resumed. With the arrangement shown the manipulation of the hand wheel is unnecessary and it is only necessary to throw over the handle 214 when it is desired to stop printing and to throw it back when printing is to be resumed, assuming, of course, that an end border B is the last section printed.

The arrangement and operation of the mechanism for printing another type of rug will be described to illustrate more clearly the complex designs which may be printed

by means of the present invention and to illustrate the ease with which the design of successive rugs may be changed while the machine is in operation.

In printing the type of rug illustrated in Figure 23 three sets of blocks are employed, two of which sets are used for printing the field design and side border sections of the rug and the third set of blocks is used for printing two oppositely faced end borders for adjacent rugs which are later to be cut apart. The blocks indicated A' A² A³ etc. print one portion of the field and side borders for the rugs, the blocks B' B² B³ print a different portion of the field and side borders for the rugs and the blocks C' C² C³ print the adjacent end borders for the rugs. In the arrangement of the portions of the design illustrated in the lefthand portion of Figure 23 the blocks are operated to cause the blocks A' A² A³ to print on the second, fourth, sixth and eighth sections of the material and are held inoperative while the first, third, fifth, seventh and ninth sections are under them. The blocks B' B² B³ print on the third, fifth and seventh sections of the material and are held inoperative while the first, second, fourth, sixth, eighth and ninth sections of the material are under them. The border blocks C' C² C³ are normally allowed to print only on every eighth section of the material, i. e., the first, ninth, seventeenth, etc. to terminate one rug design and start another.

In printing this type of rug three controllers 138^a, 138^b and 138^c are employed and three master cam elements 172^a, 172^b and 172^c are used. All of the operating rods for moving the latches 16 into and out of engagement with the lugs 20 are connected to the arm 32 of the three arm crank 26, so that when any of the solenoids are energized the latch 16 for the corresponding block is retracted and the block allowed to print.

The solenoids associated with the blocks A' A² A³ are connected to the alternate brushes A' A² A³ in the controller 138^a. If five colors are used in printing this portion of the design the brushes so connected will be the first, third, fifth, seventh and ninth. The solenoids associated with the blocks B' B² B³ are connected to alternate brushes B' B² B³ in the controller 138^b but the brushes so connected in this controller are located further around the circumference from the pin-setting solenoid as explained in previous examples and will be the eleventh, thirteenth, fifteenth, seventeenth and nineteenth. The solenoids associated with the blocks C' C² C³ are connected to alternate brushes in controller 138^c at points still further from the pin-setting solenoid, namely, the twenty-first, twenty-third, twenty-fifth, twenty-seventh and twenty-ninth brushes.

The master cam is rotated by a ratchet

having eight teeth. The master cam element 172^c which controls the operation of the pin-setting solenoid in the controller 138^c for printing the end borders of the rugs is provided with one projection 176. The master cam element 172^b which controls the operation of the pin-setting solenoid in the controller 138^b for printing the field and border blocks B' B² B³ is provided with three projections spaced circumferentially the distance of two ratchet teeth and followed by a portion having no projections for an angular distance the equivalent of three ratchet teeth. The cam element 172^a which controls the operation of the pin-setting solenoid in the controller 138^a is provided with four projections 176 spaced circumferentially the distance of two ratchet teeth. All of the master cam elements are secured together to rotate together and are located as indicated in Figure 23 so that one of the projections 176 on one of the cam elements is brought into engagement with one of the levers 178 with each forward movement of the material and with each step in rotation of the ratchet 184, the cam 172^c being set with relation to cam 172^b so that its single projection comes in the center of the portion of the cam 172^b having no projections, and the cam 172^a being set with relation to the other two so that its projections alternate with the projections on the other two.

As the master cam elements rotate starting from the position with the projection 176 on the master cam element 172^c in engagement with its lever 178, the pins are projected in the various controller rings as follows: The projection 176 being in engagement with the lever 178 associated with the controller 138^c causes a pin to be projected in the controller 178^c. With the next forward movement of the material the master cam is rotated the distance of one ratchet tooth, thus bringing one of the projections on the cam element 172^a into engagement with its lever 178 so that a pin is projected in the controller 138^a. On the next forward step the first of the three projections 176 on the cam element 172^b is brought into engagement with the lever 178 to project a pin in the controller 138^b. Continued rotation of the master cam causes a second pin to be projected in controller 138^a; then a second pin in controller 138^b; then a third pin in controller 138^a, then a third pin in controller 138^b, then a fourth pin in controller 138^a, after which the projection 176 on cam element 172^c again engages its lever 178 completing the printing cycle for the normal operation.

The location of the brushes insures the complete printing of the material by the blocks A' A² A³ etc., then a complete printing by the blocks B' B² B³ etc., after which the blocks C' C² C³ etc. print the end borders for adjacent rugs. The step by step movement

of the pins and material is the same as has been described and the printing operation is performed in the order of the pins with the various brushes connected to the solenoids 40.

In allowing an unprinted portion to pass through the machine after a complete rug with this arrangement of parts described, the operator waits until the single projection on the cam element 172^c is in engagement with the lever 178 or moves the cam as described below so that a complete rug is printed; he then moves the handle 214 to the right, retracting the pawl 186 from the ratchet and breaking the circuit for the pin-setting solenoids. Since in the arrangement illustrated in Figure 23 all of the solenoids 40 are connected to the arms 32 there must be no pins projected in any of the controllers when a section is to go through unprinted. The switch 248 may therefore be in the circuit with all of the switches 170 and the handle 214 may be thrown over at any time to pass an unprinted section regardless of the cams. An alternative arrangement would be to connect the switch 248 in circuit with only one of the switches 170, in which case if the master cam is turned so that that switch 170 is closed, the others will necessarily be open and the same result will be accomplished. When it is desired to start the printing operation again the handle 214 is moved to the left to bring the pawl again into engagement with the ratchet 184 and close the switch 248. If the last section printed upon was an end border then the next would, if no adjustment were made, be a field section A. In order to bring the projection 176 on the cam 172^c again into engagement with the corresponding lever 178 when the switch 248 is closed the hand wheel 260 is moved as described in connection with previous figures.

If it is wished to finish off a rug without printing the full sequence of eight sections various procedures may be adopted depending upon how the designs A and B fit together. Any number of the pairs of sections BA may be omitted without destroying the symmetry and finished appearance of the rug. Thus the sequence may be CAC, CABAC, CABABAC, etc. or additional sections B and A may be added by adjusting the hand wheel 260 in the manner already described. If the design B is of such a character as not to appear unfinished when apart from A then the sequence CBC, CBABC, etc. or even CABC, etc. may be printed by manipulation of the hand wheel 260 to bring the projections 176 onto the levers 178 in the required sequence. All of these changes may be made by simple manipulation of the hand wheel 260 or the handle 214 without otherwise disturbing the normal operation of the machine. Each section as it enters the machine has its fate already determined and no further thought or manipulation is required of the

operator to secure the desired result as to that section.

With this type of rug design it may be advantageous to inspect the material for flaws, etc., several steps back of the point at which the sections are when their pins are set. This permits the changing of sequence to finish off the rug as close as possible to the flaw.

10 An emergency push button 262 is provided to enable the operator manually to open the pin-setting circuit without disconnecting the pawl 186. This may be used for example when adjusting the master cam 172 if the adjustment is not complete before the timing switch 163 is about to open. Or it may be used to run a blank section into the machine by stopping the normal projecting of pins without stopping the movement of the cam.

20 In a similar way a large number of different designs of rugs can be printed with the same mechanism by simple manipulations of the master cam to cause any desired portion 25 of the design to be printed upon any desired section of the material. When the field design is made up of three or more design portions the rug pattern may be given even further variations. No attempt has been made 30 to describe all of the possible combinations or arrangements of the design sections which may be used, since innumerable designs and 35 adjustments will suggest themselves to the operator and the effectiveness of such changes will depend largely upon the design used and the ingenuity of the designer and operator.

In the present invention the machine may be adjusted to cause the sets of blocks normally to print any one of a large number of 40 designs by changing the master cam elements as desired. This change can be easily and quickly made by simply removing the cam elements previously used and substituting the new arrangement of elements in their proper relative positions. The simplicity of this substitution of cam elements and the great flexibility of operation characterizing the present invention effect a material saving in time and 45 material and make possible the printing of 50 rug designs which heretofore could not be printed satisfactorily on such machines.

The individual cams 172^a, 172^b, etc. each having a number of teeth from one to eight suitably spaced thereon may be assembled 55 in any desired combination except, of course, that all cams assembled into a master cam assembly must be designed for use with the same number of ratchet teeth. In order to provide 60 for designs involving various numbers of different sections in sequence, the ratchet wheels are also made interchangeable and assembled in the master cam assembly. The pawl 186 and its driving linkage are designed 65 to move through an arc slightly more e. g. than 72°. With an eight tooth ratchet as de-

scribed above this arc is not enough to catch two teeth at each stroke, with a seven or a nine tooth ratchet likewise only one tooth will be engaged at each stroke of the pawl and so on down to a five tooth ratchet. A four tooth ratchet could not be used since the pawl 186 would not quite catch the tooth of the ratchet 184, and a ten tooth ratchet would be moved two teeth at a time so that in effect it would not be different from a five tooth ratchet. The case is different however with a ratchet having an uneven number of teeth greater than nine. Taking for illustration an eleven tooth ratchet, the pawl 186 will at each stroke move the ratchet two teeth and as a consequence during the first revolution the intermediate teeth on the ratchet 184 and the corresponding projections or spaces on the cams 172 have no effect whatever, exactly as in the case of the ten tooth ratchet. On the second revolution, however, instead of repeating, the ratchet will stop at the positions which were skipped during the first revolution. Thus a sequence of 11, or 13 may be run on the machine without changing the throw of the pawl 186. Again with 15 teeth three at a time will be taken by the pawl, but with 16 teeth the ratchet 184 will be moved so as to stop at a different position after each movement of the pawl 186 for three revolutions, and thus a sixteen, seventeen or eighteen tooth ratchet and corresponding cam can be used to produce a sequence of sixteen, seventeen or eighteen. The number of teeth can be further increased in the same manner, omitting those numbers which are even multiples of the number of teeth engaged at each stroke of the pawl 186, until a point is reached where the projections on the cams 172 would be so close together as no longer to permit separate action upon the lever 178. Obviously if long sequences are required the lever 178 may be specially designed to avoid interference from closely spaced projections; ordinarily, however, the practical limit will soon be reached.

By the simple change of the ratchet and cams as described above the machine is at once converted for operation to produce rugs or roll goods of greater or less length and/or of greater or less complexity of design.

If a sequence of four is to be set up in the machine an eight tooth ratchet would ordinarily be chosen and the cam elements 172^a, etc., would be symmetrical, i. e. one half repeats the other half. Thus when the master cam has rotated 180 degrees the sequence is ready to begin again. Similarly with a sequence of three, cams may be used with a six tooth ratchet which repeat every 180 degrees, and for a sequence of two cams may be used with a six tooth ratchet which repeat every 120 degrees or cams may be used with an eight tooth ratchet which repeat every 90 degrees. Obviously the machine might be designed so that the pawl 186 would move farther or

not so far at each stroke and thus could be made to engage in a single revolution every tooth of a ratchet having more or less than five to nine teeth, but the maximum number of teeth that can be thus engaged in a single revolution will always be for any given pawl movement, one less than twice the minimum number (the minimum, of course, being the largest integral quotient of 360° divided by the angular movement of the pawl 186).

In Figure 23, we have also shown an alternative type of manual control which may be used with the device of our invention. This control consists of a series of switches, 262, 263, 264, 265, preferably push button switches, and a locking bar 266. A bell crank 267, actuated by the pawl 186 or any connected reciprocating part at the end of its stroke, serves to move the locking bar so as to release the switches 262, 263, 264 and 265, which are returned to their normal position by spring means. The switches may be operated and the bell crank 267 will be actuated whether the pawl 186 is engaged or disengaged, i. e. regardless of the position of the handle 214, and give a full finger-tip control of the pin setting.

In using this control, the switch 262 is first opened, e. g. by pushing the button to open the circuit through the switches 170, unless the circuit has been already opened by throwing over the handle 214. If a design A is to be printed on the section S^{42} the button 265 is depressed to close the pin setting circuit (except for the timing switch 163) to the solenoid 160 associated with the controller 138^a. This switch and also the switch 262 will be held closed by the locking bar 266 until the timing switch 163 has closed and a pin set for the section S^{42} in the controller 138^a. Almost as soon as the timing switch 163 is opened again the bell crank 267 is actuated to release the switches which have been set. If desired a separate detent may be provided for the switch 262 in order that it may be held open as long as it is desired to retain manual control without the necessity for pushing its button at each resetting. If instead of an A section a B or a C section was to be printed the corresponding button 264 or 263 would be depressed instead of 265.

Although the controller mechanism has been described as controlling only one set of blocks, each controller may be arranged to control several sets of blocks by arranging two or more retracting cams and pin projecting plungers and solenoids about the controller ring. In this way the master cam elements may be caused to control the projection of pins in different parts of one controller ring instead of different controller rings.

Although the examples specifically described above have comprised one, two or three controller mechanisms 138, it is to be

understood that any greater number may be used.

The invention is capable of many other changes in the construction, location, arrangement and adjustment of the various parts and therefore it is not intended that the invention should be limited to the particular forms and arrangements of the mechanism shown and described except as defined by the claims.

What is claimed as new is:

1. In a machine for printing rugs or the like a plurality of presses each carrying a block for printing a part of a suitable design, means for moving material under said presses step by step, a latch on each press adapted to permit or prevent the printing of its design portion on any section of the material, a solenoid for operating each latch, a lever adapted to be connected to the solenoid on either side of its fulcrum so as to convert the movement of the solenoid either to move the latch into or out of the position where it will prevent printing, means tending to move each latch to an opposite position with a force adapted to yield to that of the solenoid, a rotor adapted to rotate step by step, one step for each movement of the material through the presses, terminal conductors adjacent said rotor and spaced angularly about a circle concentric with the movement of the rotor the distance of one step movement thereof, each terminal being adapted to energize any one solenoid, contacts mounted on said rotor and equally spaced around substantially the same circle as said terminals and at points corresponding between movements of the rotor to the positioning of the terminals, means for setting any contact into contacting position before it passes said terminals, means for moving all contacts out of contacting position after they pass said terminals, a solenoid for operating said contact setting means, a cam rotated one step for each step of the material, projections on said cam, a switch operated by said projections for actuating said contact setting solenoid in a predetermined relation to the movement of the rotor so as normally to set contacts thereon in a predetermined order, means for automatically moving said cam one step for each step of the material and adapted to permit manual movement thereof to any step position between contact setting operations of the solenoid, and means for disconnecting said automatic moving means and for temporarily preventing the actuation of the contact setting means.

2. A machine as defined in claim 1 which includes a timing switch in said contact setting circuit which is closed by the operation of the machine only when the rotor is in position to bring one of the contacts into the setting position.

3. A device as defined in claim 1 in which

the latches are adapted to be locked in position by the force of the presses against them except at one point of the printing stroke and a timing switch is provided in the circuit for energizing the latch solenoids, said timing switch being operated in timed relation to the operation of the machine so that the solenoids are energized from a short period before to a short period after that point of the printing stroke is reached.

4. In a control device including a rotor which moves step by step and carries control elements each movable from an operating to an inoperative position, the combination of a rotary cam, means operated by said cam for determining the application of force to move the control elements from one position to another, and means for timing the application of said force to the control elements relative to the movements of the rotor.

5. A device as defined in claim 4 in which the cam is interchangeable with other cams determining different sequences of operation, each of such cams is driven through a ratchet secured thereto having a number of teeth equal to the number of steps in the sequence represented by the cam, and the timing means is set to operate after each movement of the ratchet is complete.

30 6. A device as defined in claim 4 in which the movement of the control elements is effective by electro-magnetic means, the means for determining the force is a switch operated by certain configurations of the cam, and the means for timing the application of the force is a second switch in series with the first and operated only when a control element is in position to be moved by the electro-magnetic means.

40 7. A device for controlling the order of operation of a mechanism which uncontrolled would operate at regular intervals which comprises means adapted to engage or be released from said mechanism at a particular point in its cycle of operation to hold it inoperative or release it for operation during the following cycle, means yieldably tending to actuate said holding means, and means for automatically timing the operation of said actuating means so that its force is applied continuously throughout the period during which the mechanism is in condition for ready engagement or release of the holding means.

55 8. In a device for controlling the operation of a plurality of mechanisms on successive portions of a piece of material, the combination of a rotor, a series of electrical circuit elements one for each section of the material from the one in the first position for operation by any of said mechanisms to the one in position for the last operation by any of said mechanisms, arranged substantially on a circle concentric with the rotation of said rotor, control elements on said rotor

arranged substantially on the same circle and each adapted to close an electrical circuit through one of said circuit elements when it is brought adjacent thereto by rotation of the rotor, the angular spacing of said control elements being such that there is one of said control elements for each portion of the material from the first to the last of said mechanisms, and the circuit elements being positioned so that at each position of the material said control elements will assume a position related to selected ones of said circuit elements as the portions of the material corresponding to said control elements are related to the mechanisms controlled by those circuit elements, and means for connecting the control for any of said mechanisms to any of said circuit elements.

9. A device for controlling the order of operations of a plurality of series of mechanisms which comprises means on each mechanism for holding it inoperative or releasing it to permit operation of the mechanism during each cycle of its operation, means associated with the holding means of each mechanism of at least one series yieldably tending to maintain said holding means in the holding position, means associated with the holding means of at least one other series yieldably tending to maintain said holding means in the released position, means associated with each holding means for moving it into the opposite position against said yieldable means, and means movable in timed relation to said mechanism adapted to actuate successively said moving means of both series in the same order as the associated mechanisms are encountered by a portion of material passing therethrough.

10. A printing machine for printing designs on material comprising a plurality of printing members each provided with a portion of the design to be printed, individual appliances for rendering each printing member alternatively operative and inoperative, a portion of said appliances when actuated operating to render printing members operative and another portion of said appliances when actuated operating to render other printing members inoperative, and mechanism for actuating said appliances adjustable to vary the order in which said appliances are actuated.

11. In a controller for a plurality of mechanisms adapted to act in succession upon a material moving therethrough, the combination of an endless carrier, controller elements mounted thereon so that each may be moved to any of a plurality of positions in which it will differently affect the operation of the controlled mechanisms, a plurality of means adjacent said carrier adapted to control said mechanisms and be actuated by said control elements on the carrier, and arranged so that they are encountered by said control

elements in the same succession as their associated mechanisms are encountered by the material, and means for moving all of the control elements to the same position, each after it has passed said adjacent control means.

12. In a controller having a plurality of means each controlling the operation of one of a number of devices intended to operate in succession upon a piece of material, actuating members movable into position to actuate the controlling means or into position to avoid actuating said controlling means, and a carriage for said actuating members adapted to move them from one controlling means to the next in the same succession that the piece of material moves from one operating device to the next, the improvement which comprises means connecting the controlling means to the operating devices adapted to be adjusted either so as to render the operating device inoperative when the controlling means is actuated or so as to render it operative when the controlling means is actuated and vice versa when the controlling means is not actuated.

13. A control mechanism as defined in claim 12 in which the adjustable connecting means comprises a pivoted lever having arms on opposite sides of the pivot and means for connecting the controlling means to either arm whereby actuation of the controlling means may be made to have an opposite effect upon the operating device.

14. A machine for printing designs in sections which comprises means for carrying forward in a step by step movement the material to be printed, printing members arranged along the path of the material each adapted to print a part of a design upon the material one section at a time, means on said members to permit or prevent the operation thereof, electrical means for operating said means, terminals in the circuit of each of said electrical operating means arranged adjacent to a rotating member, a rotating member adapted to move step by step one step for each step that the material moves forward, contacts carried on said rotor spaced the

angle moved at each step and each adapted to be moved into position to contact with and complete a circuit through the terminals or into position to avoid such contact, means for positioning said contacts on said rotor so as to energize the electrical operating means on each of a number of the printing members as any one section of material passes under each of said printing members, electrical means for actuating said positioning means and rotating means normally moved one step for each forward step of the material but capable of manual movement any number of steps for automatically or manually controlling the order in which said contacts are positioned on said rotor.

15. A machine as defined in claim 14, which further includes means for rendering inoperative the electrical means for actuating the contact positioning means.

16. A machine as defined in claim 14, which further includes means for stopping the movement of said rotating means and means for rendering inoperative the electrical means for actuating the contact positioning means.

17. A machine as defined in claim 14, in which the rotor is adapted to have a contact positioned thereon to actuate the terminals, one contact for each section of the material which enters the machine, and each electrical operating means is connected to a terminal positioned with respect to the rotor so that the contact associated with each section will contact with that terminal when the associated section of the material is in position under the printing member associated with the means for permitting or preventing the operation of said member operated from that terminal.

18. A machine as defined in claim 14, in which the rotor has a contact thereon corresponding to each section of the material which is in the part of the machine controlled by said rotor, each of said contacts being adapted to be put in an operative position where it will complete a circuit through the terminals or in an inoperative position where it cannot affect said circuit, and there is a terminal adjacent each contact, and each of said terminals is adapted to be connected with the electrical operating means on any one of the said printing members.

19. A machine as defined in claim 14, in which the means for positioning the contacts is adapted to be operated automatically in a predetermined order or manually in any desired order.

20. A multicolor printing machine for printing designs on a web of material which is fed through the machine, comprising printing members movable into and out of printing position, controlling elements that move intermittently in timed relation to the movement of the material to be printed, and appliances associated with each printing member and actuated by said controlling elements, a portion of said appliances when actuated releasing corresponding printing members so that they may move into printing position and another portion of said appliances when actuated locking corresponding printing members against movement into printing position.

21. A multicolor printing machine for printing designs on a web of material which is passed through the machine, comprising printing members movable into and out of printing position, appliances for rendering each printing member operative and inoperative, electrical circuits for actuating said

appliances, mechanism for controlling the operation of said circuits including elements that move in timed relation to the movement of the material to be printed and forming 5 parts of the circuits for controlling said appliances, and electrically-controlled means for actuating said elements to control the operation of said circuits and cause the desired ones of the printing members to be rendered operative and inoperative respectively. 10

22. A multicolor printing machine comprising printing members, means for moving the material to be printed through the machine, appliances for rendering the printing 15 members operative and inoperative alternatively, mechanism for actuating said appliances including a rotatable cam, driving means for rotating said cam in timed relation to the movement of the material through 20 the machine, means for disconnecting said driving means from the cam, and means by which the cam may be manually rotated.

23. A multicolor printing machine comprising printing members, means for moving the material to be printed past the printing members, appliances for rendering the printing members operative and inoperative alternatively, devices for actuating said appliances including elements that move in 30 timed relation to the movement of the material to be printed, a cam for automatically determining which of said elements shall be moved at any given time into position to cause said appliances to be actuated, and 35 driving means for rotating said cam movable to disconnect said driving means and to render said actuating means inoperative.

24. In a controller for mechanisms of the class described, the combination of a rotor 40 having control elements thereon adapted to be moved to inoperative or operating positions, a stationary cam for moving all control elements to the inoperative position after they have finished their operating travel, and 45 a plunger for moving each of selected ones of said control elements into an operative position before beginning its operative travel.

25. In a printing apparatus having a plurality of printing mechanisms, each adapted 50 to print a part of a design upon a unit portion of a material, a plurality of series of control elements, one series for each complete design portion for a unit portion of the material, and each series comprising one control element for each unit portion of the material within the printing apparatus, means associated with each printing mechanism for holding it inoperative and permitting operation thereof alternatively and each including 55 a part adjacent to one of said control elements so as to be operable thereby, such parts which are associated with the mechanisms which are to print on the same unit portion being arranged with respect to the same 60 series of control elements and in the same

order as their associated mechanisms are encountered by the material, and means for moving said control elements to successive ones of said holding means in timed relation to the movement of the corresponding unit portions of the material to the associated mechanisms, said control elements being adjustable on said moving means to either of two positions so as to operate or to avoid 70 operating said holding means. 75

26. A control device as defined in claim 25, in which the holding means includes a readily detachable flexible connection so as to allow it to be connected with its part in position to be operated by the control elements of any of said series. 80

27. A control device as defined in claim 25, which further comprises means for adjusting the control elements to operative and inoperative position, said means being adapted 85 to adjust to the operative position a plurality of the control elements of the several series corresponding to the same unit portion of the material, as many as may be required for producing a desired effect. 90

28. In a controller for mechanism of the class described, the combination of a series of control elements, means for moving the control elements into position to operate successively controls for different parts of the mechanism, means for positioning the control elements alternatively in operative and inoperative positions at the beginning of their travel through the control positions, means automatically determining the order in which the control elements are placed in the different positions, said determining means including a rotating cam and a ratchet drive therefor moving in timed relation to the operation of the controlled mechanisms and the travel of the control elements, and adapted to be instantly released so as to permit manual adjustment of the cam to any position between the times at which it determines the positioning of the control elements at successive steps. 100

29. In a controller for mechanism of the class described, the combination of a series of control elements, means for moving the control elements into positions to operate successively controls for different parts of the mechanism, means for positioning the control elements alternatively in operative and inoperative positions at the beginning of their travel through the control positions, means automatically determining the order in which the control elements are placed in the different positions, said determining means including a drive therefor moving in timed relation to the operation of the controlled mechanism and the travel of the control elements, means for manually disconnecting said drive and leaving said determining means in position to cause the movement into either operative or inoperative position 115 120 125 130

of all control elements which pass positioning means while the drive is thus disconnected.

30. In combination with a control device comprising means carrying a plurality of control elements movable in timed relation to a plurality of controlled mechanisms so as to bring said elements into operative relation to said mechanisms successively, each control element being movable thereon to any of a plurality of control positions in which to engage or avoid adjacent control means of certain of said mechanisms, electrically operated means for positioning the control elements on the carrying means, a rotary cam having a series of cam surfaces arranged thereon in endless sequence, means for rotating the cam so as to bring successive cam surfaces into action in timed relation to the movement of the controlled mechanisms, and a switch in the circuit of the positioning means operated by said cam surfaces.

31. A device for controlling a plurality of mechanisms so that they perform in a determined sequence the steps of a plurality of treatments required for successive portions of a material, which comprises means associated with each mechanism for determining in which of a plurality of ways it is to treat the portion of material therein, electro-magnetic means for operating each of said determining means according to a predetermined setting, means for setting the circuit of said electro-magnetic means and for automatically transferring a setting for a given sequence from one of said circuits to another in timed relation to the movement of a given section of a material from one of the mechanisms controlled thereby to another, and means for closing each circuit after the setting has been established, and for an interval slightly overlapping the period while the control mechanism is in condition to have its succeeding operation determined.

32. A device for controlling a plurality of mechanisms so that they perform in predetermined sequence the steps of a plurality of treatments required for successive portions of a material, which comprises means associated with each mechanism for determining which of a plurality of treatments is to be given the portion of material therein, means for transferring a setting for one of said treatments from one determining means to the next in timed relation to the movement into the corresponding mechanisms of the portion of the material receiving said treatment, and means for setting a part associated with the set transferring means, whereby to determine, before the section of material is acted upon by the first of said mechanisms, which treatment it is to receive, said setting means being movable to present successive portions thereof in a closed cycle, and each portion being adapted to impart the setting

required for one of the sequences, and being arranged to come into the operative position in the same order as said treatments are desired, automatic means for moving said setting means so as to bring successive portions into the operative position in timed relation to the entry of successive sections of the material into the first mechanism, and manual means for moving said setting means so as to bring any of the successive portions thereof into the operative position without disturbing the continued automatic operation of the series at the point at which it is left by the manual operation, and means for preventing the intermediate portions of the setting means from affecting the setting when they are moved through the operative position.

Signed at Philadelphia, Pennsylvania, this 29th day of January, 1930.
